UNITED STATES PATENT OFFICE.

EMORY M. FRASIER, OF SAN FRANCISCO, CALIFORNIA, ASSIGNOR OF ONE-THIRD TO
GEORGE B. SEAMAN AND ONE-THIRD TO AGNES D. SEAMAN, BOTH OF SAN FRAN-
CISCO, CALIFORNIA.

ELEVATOR-DOOR SAFETY DEVICE.

1,106,294.

Specification of Letters Patent.

Patented Aug. 4, 1914.

Application filed October 21, 1911. Serial No. 656,050.

To all whom it may concern.

Be it known that I, EMORY MELVON FRASIER, a citizen of the United States, and a resident of the city and county of San Francisco, State of California, have invented a new and useful Elevator-Door Safety Device; and I do hereby declare the following to be a full, clear, and exact description of my invention, such as will enable others skilled in the art to which it appertains to make and use the same.

My invention relates to an elevator safety device which makes impossible the starting or operating of an electric elevator passenger or freight car from a station or landing while the entrance door at any station or landing in the system is open.

The object of my invention is to prevent injury to passengers or operatives. In a system equipped with my safety device it is impossible to operate the car unless all entrance doors are shut. Opening any of the entrance doors while the car is in operation automatically stops the car.

In the drawings, wherein like letters indicate like parts: Figure 1, is a top view of the entire apparatus with the cover removed; Fig. 2, is an interior view taken on the line X—X of Fig. 1, looking toward the center as it would appear with the cover *x* in its place; Fig. 3, is an external view of the conduit end; Fig. 4, is a cross section on line Z—Z of Fig. 1, looking toward the center; Fig. 5, is an external view of the bolt end; and Fig. 6, is a section on line Y—Y of Fig. 1, looking toward the center and places of contact.

In detail, the construction consists of the case or box, *a*, lined with a fiber insulation, *i*. The block, *u*, is of fiber or a non-conductor carrying the spring brass contact blades, *t*, which are secured by the block screws, *g*. The block *u* is held in position by the screws *c*, which pass through that portion of the block designated by the letter *v*, and the same extends to the underside of the cover insulation, *i*, and acts as a barrier or fire-wall between the two points, *e*, at which places are connected the wires, *b* and *b'*, which lead to the electric magnet device (not shown but a necessary part of the elevator apparatus) which regulates and controls the elevator operating power. These wires, *b* and *b'*, are carried from the said magnet control

through a conduit (not shown) to each station door where my safety device is located. The hub, *w*, of the box, *a*, is threaded to receive the said conduit. The wires, *b* and *b'*, pass through the said conduit and enter the box, *a*, through the hub, *w*, and the holes, *b*' and *b*, cut in the insulation, *i*.

The bolt, *l*, Figs. 1 and 2, is shown to be in contact position with the blades, *t*, as it will be held by the elevator door when the same is closed. When the door is opened the action of the spring, *n*, will force the bolt, *l*, out and away from contact with the said blades, *t*, to a position indicated by the dotted lines, *m*. In closing, the door strikes the rubber bumper, *o*, on the end of the bolt, *l*, and forces the same into the position shown by the drawings (Figs. 1 and 2). When the door is closed a complete-wipe contact is made between the two blades, *t*, by the hard copper plate, *h*, attached to the fiber block, *s*, by the screws, *j*. The contact blades, *t*, are slotted, as at *a'*, to give a sure bearing on the said plate *h*. The block, *s*, is fastened to the bolt, *l*, by the screws, *r*. In the bolt, *l*, is a groove or slot, *k*, which acts as a guide in conjunction with the post, *q*. Behind the post, *q*, and inside of the bolt, *l*, there is a heavy spring, *n*, which forces the said bolt into the position indicated by the dotted lines, *m*, when the elevator door is opened. As long as the door remains open and the bolt, *l*, is in this position (*m*) with the contact surfaces of the members *h* and *t* apart the circuit is disconnected and the car is then without power and cannot be started. It is necessary, therefore, that the circuit must be completed by closing the door before the car can be operated.

The holes, *f*, are provided so that the box, *a*, may be fastened in position on the inside face of the elevator front or grill-work at a point near the top of the door. Holes, *d*, are provided with threads to receive the screws, *y*, which hold the cover plate, *x*, in position. Screw *p* is tapped into the end of the bolt, *l*, to hold the rubber bumper, *o*, in position.

It will be noted that my device is compact, easily accessible, dust proof and perfectly insulated. The contact is always assured and that there is no possibility of a jump or a hanging fire.

Having thus described my invention what

I claim and desire to secure by Letters Patent is:

1. A safety switch for elevator doors, including an inclosed base; a pair of insulated contacts fixed on said base; a post extending above the plane of said base; a plunger having a slot engaging said post; a contactor mounted on said plunger in alinement with said fixed contacts; and a spring interposed between said post and the end of said slot in said plunger.
2. A safety device for elevator doors including a base; a pair of insulated contacts fixed on said base; an insulated block having a wip-

ing contact plate thereon slidable between 15 said contacts; a plunger fixed to said insulation block; a slot in said plunger; a post on said base extending through said slot; and a spring interposed between said post and the end of said slot.

In testimony whereof I have hereunto set my signature in the presence of two subscribing witnesses.

EMORY M. FRASIER.
